[57] CLAIM

The ornamental design for a combined bottle and cap, as shown and described.

DESCRIPTION

FIG. 1 is a front elevation of a combined bottle and cap showing my new design, the rear and side elevations are the same;

FIG. 2 is a top perspective view of the combined bottle and cap design;

FIG. 3 is a bottom perspective view of the combined bottle and cap design;

FIG. 4 is a top plan view of the combined bottle and cap design;

FIG. 5 is a bottom plan view of the combined bottle and cap design;

FIG. 6 is a side elevational view of the combined bottle and cap design with the cap shown separated;

FIG. 7 is a perspective view of the combined bottle and cap design with the bottle shown in a top perspective view and the cap shown separated in a bottom perspective view.

The drawings are lined to indicate a contrasting color.
